SPEED GOVERNING APPARATUS FOR INJECTION INTERNAL COMBUSTION ENGINES

Alfred Schweizer, Stuttgart, Germany, assignor to Robert Bosch Aktiengesellschaft, Stuttgart, Germany

Application September 1, 1936, Serial No. 98,950
In Germany September 27, 1935

6 Claims. (Cl. 123—140)

This invention relates to speed-governing apparatus for injection internal combustion engines of the type wherein the amount of fuel injected is controlled by a pneumatic governor 5 operated by the pressure in the engine air supply pipe in which a voluntarily adjustable throttle member is provided.

An object of this invention is to ensure that the governor may operate even when the engine 10 is reversed and when the throttle valve may not be quite tightly closed as otherwise the engine may attain a speed considerably in excess of the idling speed, and one at which the engine can give out an appreciable output. If now for example a strongly throttled engine running idle 15 should suddenly run in the reverse direction, and the driver in ignorance of this starts the vehicle, the vehicle, in spite of a safety device against uncontrolled running of the type in which a by-pass is provided in the engine air supply pipe 20 and in communication with the governor, which by-pass extends to opposite sides of the throttle valve in said pipe and is proportioned so that with the throttle valve closed, the maximum volume 25 of air capable of passing through the by-pass is that volume enabling idle running only of the engine, could unintentionally run backwards and cause damage, before the engine was again de-clutched and the vehicle braked. In order to 30 avoid these possibilities, by the arrangement according to the present invention a reduction in the speed of a reverse running internal combustion engine to the idle running speed, or even a stopping of the engine, is obtained.

The arrangement of this invention consists in a non-return valve, which during the running in the normal direction of rotation allows a part 40 of the air amount for idle running to enter the space behind the throttle-valve, but which on reverse flow impulse in the induction pipe and whenever the engine reverses, closes, wholly or at least for the greater part its previously free cross-section, so that on the reverse running of the engine a current that is at least as strong 45 as occurs there during the running of the engine in the usual direction of rotation prevails in the by-pass which remains uninfluenced by the throttle member, and to which the servomotor is connected.

Three different examples of construction of the invention are shown in the accompanying drawing in which:—

Figure 1 shows in section a part of an injection 55 pump and the induction pipe of the engine.

Figure 2 shows the same parts on another possible construction, and

Figure 3 shows the same parts in a third example of construction.

In Figure 1, 1 is the casing of a fuel injection pump of known construction, having a cam-shaft 2 and pump pistons 3, which are rotated about their axis by a toothed rackbar 4. According to the degree of this angular movement, the separate pumps can deliver more or less fuel into 10 the cylinders of the internal combustion engine to be governed. A pneumatic governor is built on to the casing 1, and its piston 5 can adjust the rackbar 4, and its casing 6 is connected by a pipe 7 to the induction-pipe 8 of the engine 15 and at the other side by the opening 6' with the atmosphere. The free cross-section of the induction-pipe 8 for the passage of air can be controlled by the throttle-valve 9, which can be adjusted by the driver by means of the rod 10 and 20 the pedal lever 11. The throttle-valve 9 oscillates in a Venturi-tube insert 12 arranged in the induction-pipe 8.

In the most contracted part or throat of this 25 Venturi-insert 12 a by-pass divided off from the throat passage is arranged, through which a part of the induction air can flow independently of the 30 rocking movement of the throttle-valve 9. The by-pass consists of a symmetrical auxiliary venturi 13, whose long axis lies parallel to that of the induction-pipe 8, and to the centre of which the pipe 7 leading to the casing 6 of the pneumatic governor is connected, the end of the pipe 7 projecting into the contracted part of the 35 venturi. The ends of the auxiliary Venturi tube 13 do not however extend beyond the cylindrical 40 part of the throat of the Venturi insert 12.

The auxiliary venturi 13 lies with its induction air end within the path of swing of the throttle-valve 9, which is slotted on this side and in the idle running position engages with this slot over the auxiliary venturi 13, so that its induction opening remains open even when the throttle-valve is closed.

According to Figure 1, a still further passage 45 for a further part of the induced air is provided in the throat of the Venturi insert 12, which passage, according to the invention, is only open during the flowing of the induction air, and automatically closes on the engine running in the reverse direction. In the throttle-valve 9 itself a non-return valve is arranged, consisting of a 50 springy flap 14, which can close an opening 15.

This arrangement works in such a way that, 55

on the ordinary working direction of rotation of the engine, the air is drawn through the induction pipe 8 in the direction of the arrow A. In the idle running position shown, the induction 5 air will flow through the gap round the throttle-valve 9 and through the non-return valve in the throttle-valve, and further, in this case a sufficient current will exist in the by-pass of the auxiliary venturi 13 arranged in the Venturi insert 12, so that through this auxiliary venturi a 10 sufficient degree of vacuum is produced at the end of the pipe 7, to operate the pneumatic governor.

On a change in the direction of rotation of the 15 engine, the cylinder charge is forced through the induction-pipe in the direction of the arrow "B". The passage through the opening 15 of the closed throttle-valve 9 is now closed by the non-return valve, and the whole charge of the cylinder goes 20 through the symmetrical auxiliary venturi 13, in which it produces the vacuum necessary for operating the pneumatic governor. As the current flowing backwards through the auxiliary venturi 13, owing to the closing of the non-return 25 valve, is at least as great as that during the induction of the air on the normal direction of rotation of the engine, an equally high vacuum can act on the pneumatic governor on the reverse 30 running of the engine, and its piston 5 will move the controlling rod 4 in such a way as to keep the amount of fuel delivered by the pistons 3 the same as during idle running. This vacuum may 35 also be so strengthened by making the auxiliary venturi 13 in the Venturi insert 12, of suitable dimensions that the pneumatic governor entirely stops the engine in a short time after it starts to run in reverse.

The construction shown in Figure 2 shows a 40 one-winged throttle-valve 9a in the idle running position, this valve itself acting as the non-return valve. The rod 10a of the throttle-valve, when the engine is running idle, strikes on a stop 16, which is held in the position shown under the 45 pressure of a spring 17. When the reverse flow impulse and movement of the cylinder charge in the direction "B" occurs, the throttle-valve is quite closed, while the lever rod 10a moves the stop 16 into its end-position against the pressure of the spring. On the full closure of the passage 50 through the induction-pipe, a current is set up in the by-pass 18, provided with a venturi 13a, which is as strong as, or stronger than, the current occurring during the induction of the air, so that in this way an equally great or increased 55 vacuum acts on the pneumatic governor, which causes a reduction in the engine speed to the idling speed, or a stoppage of the engine.

The part of the air for idle running which 60 passes behind the throttle member on the induction stroke, but whose entrance thereto is prevented on the reverse running of the engine, may also pass through an auxiliary opening 19 into the induction-pipe 8, and the auxiliary opening situated in front of the throttle-valve 9 may be 65 closed by a flap valve 20. In this arrangement also, which is shown in Figure 3 on the reverse running of the engine, a current will enter the by-pass 18 which is at least as great as or greater 70 than the amount of air entering through the auxiliary opening 19, which enables the engine to continue to run idly or a stopping of the engine on reverse running.

I declare that what I claim is:

75 1. A speed governing apparatus for injection

internal combustion engines comprising an air supply conduit, a voluntarily adjustable throttle valve, a pneumatic governor operated by the pressure in said conduit and controlling the supply of fuel to said engine, a by-pass in said air supply conduit extending to opposite sides of said throttle valve when closed and in communication with said governor, said by-pass being proportioned so that with the throttle valve closed the volume of air capable of passing through the by-pass is only a part of that volume which enables idle running of the engine, and an automatic one-way valve controlling flow in said air supply conduit and thereby influencing flow in said by-pass.

2. A speed governing apparatus for injection internal combustion engines comprising an air supply conduit, a voluntarily adjustable throttle valve, a pneumatic governor operated by the pressure in said conduit and controlling the supply of fuel to said engine, a by-pass in said air supply conduit extending to opposite sides of said throttle valve when closed and in communication with said governor, said throttle valve being provided with means cooperating therewith to form an automatic one-way valve controlling flow in said air supply conduit and thereby influencing flow in said by-pass.

3. A speed governing apparatus for injection internal combustion engines comprising an air supply conduit, a voluntarily adjustable throttle valve, a pneumatic governor operated by the pressure in said conduit and controlling the supply of fuel to said engine, a by-pass in said air supply conduit extending to opposite sides of said throttle valve when closed and in communication with said governor, a venturi in said by-pass, said by-pass being proportioned so that with the throttle valve closed the volume of air capable of passing through the by-pass is only a part of that volume which enables idle running of the engine, and an automatic one-way valve controlling flow in said air supply conduit and thereby influencing flow in said by-pass.

4. A speed governing apparatus for injection internal combustion engines comprising an air supply conduit, a venturi in said conduit, a voluntarily adjustable throttle valve in said venturi, a pneumatic governor operated by pressure in said conduit and controlling the supply of fuel to said engine, a by-pass in said air supply conduit extending to opposite sides of said throttle valve when closed and in communication with said governor, a venturi in said by-pass, said by-pass being proportioned so that with the throttle valve closed the volume of air capable of passing through the by-pass is only a part of that volume which enables idle running of the engine, and an automatic one-way valve controlling flow in said air supply conduit and thereby influencing flow in said by-pass.

5. A speed governing apparatus for injection internal combustion engines comprising an air supply conduit, a voluntarily adjustable throttle valve in said air supply conduit, a one-way valve carried by said throttle valve, a pneumatic governor operated by the pressure in said conduit and controlling the supply of fuel to said engine, and a by-pass in the air supply conduit extending to opposite sides of said throttle valve when closed and in communication with said governor.

6. A speed governing apparatus for injection internal combustion engines comprising an air supply conduit, a throttle valve, means for vol-

unitarily adjusting said throttle valve, a pneumatic governor operated by the pressure in said conduit and controlling the supply of fuel to said engine, a by-pass in said air-supply conduit extending to opposite sides of said throttle valve when closed and in communication with said

governor, and means cooperating with said throttle valve when it approaches the closed position permitting said valve to act as an automatic one-way valve controlling flow in said air supply conduit.
